UNITED STATES PATENT OFFICE.

JAMES M. GREEN, OF CHICAGO, ILLINOIS.

MACHINE FOR PHOTOGRAPHIC LIGHTING.

1,321,521.

Specification of Letters Patent. Patented Nov. 11, 1919.

Application filed November 30, 1918. Serial No. 264,835.

To all whom it may concern:

Be it known that I, JAMES M. GREEN, a citizen of the United States, residing at the city of Chicago, county of Cook, and State 5 of Illinois, have invented a new and useful Improvement in Machines for Photographic Lighting, of which the following is a specification.

My invention relates to machines for 10 lighting photographic studios, and other similar work where photographic plates or films are used, and one of the objects of my invention, is to secure a maximum of results upon the plate or film, from a minimum 15 of illumination. As is well known, the emulsion employed on the ordinary photographic plate or film is highly sensitive to the light from the violet end of the spectrum, but only very slightly affected 20 by the light from the remainder of the spectrum. As a result, only a very small portion of the light usually employed known as white light is of any effect, as only a small portion of it consists of the 25 violet rays.

To accomplish my said object I employ a machine for lighting in which I arrange a special combination of adjustable clear and colored lights and colored reflectors, so 30 arranged that all of the colors are blended to produce a violet ray, and adjustable so that the entire illumination may be directed upon the objects to be photographed, thereby securing a maximum of results 35 from the illumination.

The above, and other objects are secured by the special means illustrated in the accompanying drawings and described in the following specification and therein more 40 particularly pointed out and claimed.

In the drawings forming part of this specification, in which like numerals of reference refer to similar parts throughout the various views,

45 Figure 1 is a front elevation of one style of my machine as designed for lighting photographic studios.

Fig. 2 is a side elevation of the same.

50 Fig. 3 is a sectional view of the lighting head, along the line 3—3 of Fig. 1, showing the arrangement and relative location of the various parts employed.

Fig. 4 is a detail view of one of the adjustable lighting units, with reflector.

55 Referring to the accompanying drawings,

I have shown my machine as supported upon a standard 1, which may be of any usual design, but I have preferably shown it as supported upon a pedestal having feet at 2. I have also preferably shown a standard 60 in which the parts are made to telescope as shown at 3, to permit the raising and lowering of the lighting head, as may be required in operation. At 4 in the standard I have provided an adjustable joint for the 65 purpose of adjusting the lighting head forward or backward, as may be required for the special service for which it is used. This adjustable joint is especially shown in the detail drawing at Figs. 1 and 2.

70 The lighting head consists of the outer casing, or body part 5, containing and supporting the other parts hereinafter described, which said casing is of substantially the form shown. It is suitably wired 75 for electric light service which is not shown, one wire being carried to each of the light units hereinafter described. At the front of said casing, I have provided an open case 13 for holding the screen 10 and 80 the lens 11. Said case is hinged to the casing at 14 and has a suitable catch for holding it in position at 15, thus permitting the free opening and closing of said case for convenience in adjusting the lighting units, 85 and the reflectors, as hereinafter more particularly described.

86 In my illustration Fig. 1, I have shown a design arranged for seven incandescent lights, one in the center, and one at each point 90 of a hexagon surrounding said center, and have indicated them by the numeral 7. Arranged in the rear of each light, I have provided a small reflector 8, arranged to throw the light from the light in front of 95 it, directly forward. In the rear of these reflectors, and forming a large reflector to reflect forward any rays which may not be reflected forward by the individual reflectors 8, I have provided the large reflecting surface 9, which is concave in its middle portion, as shown, and has a flange directed outwardly at a suitable angle at its outer surface.

100 I have constructed each of the outer light 105 unit sockets with an adjustable joint, 16, as shown in detail in Fig. 4, so arranged as to permit each lighting unit to be adjusted toward the center, or away from the center thus affording a ready facility for adjust- 110

ing the lights to throw the full lighting upon the particular objects desired to be illuminated.

In front of said lights, I have provided 5 the lens 11, for the purpose of condensing the rays of light upon any particular object, and also for the purpose of blending the rays from the various light units, as they reach the object. I have also provided, 10 in the rear of said lens, the screen 10, which is also adapted to break up the light coming from the various light units, and to blend them into one harmonious shade.

In practice, I find that I secure the best 15 results by employing seven or more lights, arranged as shown in Fig. 1, with a large clear electric lamp at the center, having a clear or polished reflector in its rear, while arranged about it in their order, I employ 20 smaller electric lamps, (the shade of each lamp and its individual reflector being the same,) colored rose madder, cobalt blue, crimson lake, pink madder, carmine and Prussian blue. The reflector 9 I preferably 25 tint blue, thereby providing a reflection for any rays escaping from the individual reflectors 8 which will blend them into the one common tint desired to be attained.

By this construction and arrangement, 30 I secure a combination of colors which forms the nearest approximation to violet ray which has heretofore been produced, and a color which can be directed directly upon the objects to be illuminated, and which will 35 produce the maximum of effect upon the photographic plate or film employed without other color screen, or other device employed heretofore to harmonize the colors, and each of which greatly retards the time 40 of exposure.

While I have illustrated and described my invention as employed for photographic purposes in photograph studios, and the like, I do not wish to be confined exclusively to that class of work, as the same 45 arrangement may be equally well employed in making negatives for moving picture films, for printing moving picture films from such negatives, for making lantern slides 50 and transparencies, and for use in the usual work of printing on photographic papers.

Having thus described my invention, what I claim and desire to secure by Letters Patent, is the following:

55 1. In a lighting system for photographic lighting, the combination of a large reflector; several lighting units adjustably mounted in front of said reflector; an adjustable

reflector mounted in rear of each of said light units; a screen supported in front of 60 said light units, and a lens supported in front of said light units, substantially as shown and described.

2. In a lighting system for photographic studies and the like, the combination of a 65 reflector adjustably mounted upon a support; a plurality of light units mounted in front of said reflector; individual reflectors mounted in rear of each of said light units; a screen mounted in front of said light units, 70 and a lens also mounted in front of said light units, substantially as shown, and for the purposes set forth.

3. In a system for photographic studio lighting and the like, the combination of a 75 reflector tinted blue, having one central clear light mounted in front of it, and a plurality of colored lights mounted in front of said reflector; each of said colored lights being adjustably mounted, and each of said 80 colored lights having an individual reflector of the same tint as itself; a screen mounted in front of said lights, and a lens also mounted in front of said lights, substantially as shown, and for the purposes set forth. 85

4. In a lighting system for photographic studios and the like, the combination of a 90 large reflector; seven light units and seven individual reflectors, one in the rear of each light unit; said light units having the colors clear, rose madder, cobalt blue, crimson lake, pink madder, carmine and Prussian blue; each individual reflector having the same color as its respective light unit; a screen for blending said colors; a lens also 95 for blending said colors to produce an approximation of the violet ray, substantially as shown, and for the purposes set forth.

5. In a device for lighting photographic studios, and the like the combination of a 100 lighting head adjustably mounted upon an adjustable standard; lighting units within the lighting head adjustably mounted; a reflector in the rear of each lighting unit, a 105 larger reflector in the rear of all the lighting units and reflectors aforesaid; a screen in front of said lighting units; and a lens also in front of said lighting units, all as shown and for the purposes set forth.

In testimony whereof, I have hereunto set 110 my hand in the presence of two subscribing witnesses.

JAMES M. GREEN.
